STRAIN RELIEF FOR ELECTRICAL CONNECTORS

Lester L. Ladd, Lockport, Ill., assignor to George D. Ladd, Lockport, Ill.

Application April 10, 1937, Serial No. 136,158

-4 Claims. (Cl. 173—322)

My invention relates to electrical terminals and particularly to plug connectors such as are used for connecting conductor cords to electrical outlets and to electrical appliances.

Devices of this type usually comprise a body portion of insulating material having mounted therein or thereon a plurality of socket or pin type contacts. The conductors of the electrical cord with which the connector is used are connected to the contacts by suitable screws or the like.

During the use of appliance cords and similar devices, it is common practice to effect the disconnection of the cord from the associated outlet or appliance by a pulling or jerking action and, to assure reasonably satisfactory operation of the cord and connector over a substantial period of time, it is necessary to provide some means, in the nature of a strain relief, for preventing the stresses induced by such pulling or jerking from being transmitted to the connection between the cord conductors and the connector contacts. In fact, this matter is of such a serious nature, both from the viewpoint of assuring satisfactory long operative life of the connector and a minimization of fire hazard, that the insurance underwriters have required that an approved connector of the above described type must be capable of sustaining a weight of twenty pounds applied across the contacts thereof and the associated cord for a period of five minutes without causing separation of the cord and the contacts, when the screws for fastening the cord conductors to the contacts have been backed off one-half turn.

The main objects of the present invention are to provide an improved strain relief of simple construction for mechanically interconnecting the cord proper with the body portion of the connector so as to prevent the stresses induced during use of the connector from being transmitted to the electrical connection between the cord conductors and the connector contacts; to provide an improved strain relief which may be embodied into existing connector plug structures without any modification thereof; to provide an improved strain relief which may be applied laterally to the cord with which it is used; and to provide an improved strain relief of the subject type which shall utilize a minimum of parts and which shall be inexpensive to manufacture and to install.

An illustrative embodiment of the invention is shown in the accompanying drawing, wherein—

Figure 1 is a side elevation partially broken

away of an appliance type connector plug utilizing a strain relief in accordance with the present invention;

Figure 2 is a sectional view, partially in elevation, taken on the general line 2—2 of Figure 1;

Figure 3 is an enlarged plan view of the strain relief of the present invention as applied to the conductor cord with which it is used;

Figure 4 is a view similar to Figure 3, but showing an intermediate position in the applying of the strain relief to the cord with which it is used;

Figure 5 is a sectional view on the general line 5—5 of Figure 3;

Figure 6 is a side elevation of the strain relief applied to the conductor cord with which it is used;

Figure 7 is a perspective view of the strain relief in the assembled position with its cord gripping disks open;

Figure 8 is a perspective view of the two disks of the strain relief when disassembled.

Figure 9 is a perspective view of a locking spring which preferably forms a part of the strain relief; and

Figure 10 is a side elevation, partially in section, of a connector cap, such as is commonly utilized at the outlet end of an appliance cord, embodying a strain relief in accordance with the present invention.

Referring to the drawing, the appliance type connector therein illustrated includes a suitable body or grip portion comprising two complementary members 1 which may be of molded insulating material and which are releasably secured together, as by a bolt 2 or other suitable means. Suitable recesses 3 are formed in the inner faces of the body forming members 1 for receiving a pair of socket type contacts 4 which are adapted to releasably engage the contact pins forming a part of the appliance with which the connector is used. The conductors 5 of the cord 6 are connected to the upper ends of these contact elements 4 by suitable screws 7 or similar means.

To minimize bending and kinking of the cord adjacent the connector, the connector includes an axially flexible protector spring 8, the lower coils 9 of which occupy an annular recess 10 formed in the cooperating members 1 making up the body portion of the connector. If desired, the upper end of the protector spring 8 may be provided with a ferrule 11 of insulating material encircling the cord proper.

- In the preferred embodiment of the invention shown, the strain relief comprises a pair of cord grips taking the form of a pair of disks 12 and 13, with centrally located slots 14 and 15, respectively, in order that the disks may be applied laterally to the cord conductor with which the strain relief is used. The members 12 and 13 are preferably punched from sheet insulating material such as hard fiber. The slots 14 and 15 are of somewhat less width than the normal diameter of the conductor cord, in order that the strain relief shall at least slightly compress and very tightly grip the conductor cord when in position thereon, as is illustrated in Figure 5, and are formed with flaring open ends to facilitate the entrance of the cord and with concave inner ends which hug opposite sides of the cord when the disks are fully closed on the cord as shown in Fig. 3.
- The disks 12-13 are hinged together by means of a spring wire 16 which is bent to the form shown in Figures 3, 4, 5, 6, 7 and 9. The spring includes a hinge pin section 17 which passes through apertures 18, 19 in the disks 12, 13, respectively, laterally opposite the slots. The extremity 20 of the spring, adjacent the hinge pin section, is bent against the disk 12 so as to secure the disks against accidental disengagement. The intermediate portion of the spring 30 forms a clip 21 which is looped around a portion of the disk 12 and extends into peripheral recesses 22, 23 formed in the disk 12 so as to lock the spring in proper position.
- The end of the spring which is seated in the recess 23 forms a latch 24 which is adapted to enter a peripheral recess 25 in the disk 13 for locking the two disks in the assembled position shown in Figures 3, 5 and 6. Adjacent the recess 25, the periphery of the disk 13 is formed to provide a cam 26 which is adapted to engage the latch 24, as shown in Fig. 4, as the disks are pressed edgewise toward each other for urging the latch outwardly so as to permit it to snap into the recess 25 when the recesses 23 and 25 are brought into alignment, as shown in Fig. 3.
- With this improved construction, each of the washers or disks serves as a gate for closing the open end of the slot of the other disk.
- The manner of attaching the strain relief is illustrated particularly in Figures 3 and 4. Either of the two disks 12 and 13 is applied laterally to the conductor cord at the desired location thereon and the other disk is then swung on its hinge into engagement with the cord.
- As the two disks approach the operative position, the cam 26 rides on the latch 24 so as to urge the latch outwardly until it snaps into the recess 25 for locking the parts in operative position.
- The proportions of the slots 14 and 15 in the two disks are, as mentioned previously, such that when those members are in the assembled position they very tightly grip the conductor cord with which the strain relief is used and, by virtue of the fact that the stresses induced in the spring 16 which serve to latch the two disks together are of a shearing nature, there is no tendency for the various elements of the strain relief to become disengaged during use thereof.
- If the strain relief is used in conjunction with an appliance type connector, such as that illustrated in the drawing, the outer dimensions of the strain relief are preferably so proportioned that the strain relief may be fitted within the lowermost coils 9 of the protective spring 8 which

prevents excessive bending of the conductor cord 6. When in that position the strain relief will abuttingly engage the adjacent upper coils of that spring and will mechanically connect the conductor cord 6 to the body portion of the connector plug with a resilient connection. Thus, none of the stresses which may be induced in the cord 6 during use of the connector will be transmitted to the electrical connection between the cord conductors 5 and the socket terminals 4 of 10 the connector.

When the strain relief is used in conjunction with other types of connectors, such as plug caps and the like, the proportions of the two disks may be conveniently correlated with the dimensions of such other connectors to accomplish the desired mechanical interconnection of the cord and the connector. A particularly suitable arrangement is illustrated in Figure 10. The strain relief in this device abuttingly engages a suitable 20 annular recess 27 formed in the body portion 28 of a plug cap 29.

From the foregoing, it will be seen that I have provided an improved strain relief of novel design which may be readily applied to various 25 types of existing connector structures without any material modifications thereof. My improved strain relief is very simple in design, and it is easy and inexpensive to manufacture. My improved strain relief is particularly easy to install, for the reason that the two elements thereof need not be slipped over the end of the conductor with which the device is used, but may be applied laterally to the cord at any desired 30 point, either before or after the cord conductors have been connected to the terminals with which they are used. The ability of being laterally applicable to the cord is of the greatest importance in minimizing assembling costs, and in 35 making possible many of the most desirable features of the invention.

Although but one specific embodiment of the invention has been herein shown and described, it will be understood that details of the construction shown may be altered without departing 40 from the spirit of my invention as defined by the following claims.

I claim:

1. The combination with a compressible conductor cord, of a strain relief for application to said cord comprising a disk having an open-ended slot to permit said disk to be applied edgewise to the cord, said slot being of less width than the diameter of said cord whereby said disk is adapted to pinch the cord, a gate for closing the open end of said slot to secure said disk against removal from the cord, and a wire for locking said gate in closed position, said wire having a portion embracing a portion of said disk, a portion forming a hinge pin for connecting said gate to said disk, and a portion separately engaged with said gate to lock the latter in closed position.

2. The combination with a compressible conductor cord, of a strain relief for application to said cord comprising a disk having an open-ended slot to permit said disk to be applied edgewise to the cord, said slot being of less width than the diameter of said cord whereby said disk is adapted to pinch the cord, a gate for closing the open end of said slot to secure said disk against removal from the cord, said gate formed with a peripheral notch, and a spring wire for locking said gate in closed position, said wire 75

5 having an intermediate portion embracing a portion of said disk, one end portion forming a hinge pin for connecting said gate to said disk, and its other end portion serving as a latch cooperating with said notch for automatically locking said gate in closed position.

10 3. A strain relief for application to a cord comprising a pair of overlapping flat cord grips having opposed open-ended slots for receiving the cord, each of said grips serving as a gate for closing the open end of the opposed slot, and a spring wire embracing a portion of one of said grips, said spring wire having a portion serving as a hinge pin for hingedly connecting said grips together and having another portion serving as

15 a resilient latch for locking said grips in operative position.

4. The combination with a compressible conductor cord, of a strain relief for application to said cord comprising a pair of overlapping disks having opposed open-ended slots for receiving the cord, at least one of said slots being of a width less than the diameter of said cord so as to permit its disk to pinch the cord, each of said disks serving as a gate for closing the open end of the opposed slot, and a spring wire embracing a portion of one of said disks, said wire having a portion serving as a hinge pin for pivotally connecting said disks to each other.
